Primary Examiner—James M. Gandy*Assistant Examiner*—M. Brown*Attorney, Agent, or Firm*—Edgar A. Zarins; Malcolm L. Sutherland[57] **CLAIM**

The ornamental design for a disc brake shim, as shown and described.

DESCRIPTION

FIG. 1 is a perspective view of a disc brake shim showing our new design;

FIG. 2 is a front elevational view thereof;

FIG. 3 is a top plan view thereof;

FIG. 4 is a bottom plan view thereof; and,

FIG. 5 is a side view thereof, the opposite side being a mirror image of the side shown.
